UNITED STATES PATENT OFFICE.

SOLOMON WILE, OF ROCHESTER, NEW YORK.

SLICING MACHINE.

Application filed July 14, 1922. Serial No. 574,202.

To all whom it may concern:

Be it known that I, SOLOMON WILE, a citizen of the United States, and resident of Rochester, in the county of Monroe and 5 State of New York, have invented certain new and useful Improvements in Slicing Machines, of which the following is a specification.

The present invention relates to slicing 10 machines and more particularly to the type in which a segmental guard is provided for a rotary cutting blade. An object of this invention is to provide in connection with a segmental guard a combined stripper and 15 guard which, when in stripping position, will cooperate with a grooved member axially arranged with reference to the rotary cutter. Another object of the invention is to provide an improved means of holding 20 the segmental guard in cooperative relation with the rotary cutting blade. Still another object of the invention is to provide a collector for the sliced material, supported from the segmental guard in a novel manner.

25 To these and other ends, the invention consists of certain parts and combinations of parts, all of which will be hereinafter described, the novel features being pointed out in the appended claims.

30 In the drawings:

Fig. 1 is a front view of a slicing machine constructed in accordance with this invention;

35 Fig. 2 is a fragmentary plan view of the machine;

Fig. 3 is a detail view of the segmental guard in its lower position;

40 Fig. 4 is a detail view, showing the manner in which the segmental guard is held in operative position;

Fig. 5 is a detail view, showing the connection between the segmental guard and the combined stripper and guard;

45 Fig. 6 is a detail view, showing the manner in which the combined stripper and guard cooperates with the grooved member on the shaft of the cutting disk; and

50 Fig. 7 is a detail view, showing the manner in which the collector for the cut material is supported for the guard.

Referring more particularly to the drawing, 1 indicates the base frame on which the rotary cutting blade 2 is mounted to turn. On the base frame, a longitudinally movable 55 carriage 3 is mounted and this carriage supports a transversely movable carriage 4 on

which a meat clamping means 5 is arranged. These features do not form any part of the present invention and are not shown or described in detail.

Pivoted on the shaft 6 on the base of the frame 1 is a segmental guard 7, which covers the greater portion of the rotary cutting blade 2, leaving an exposed portion for cooperating with the material to be cut, arranged on the transversely movable carriage 4. This segmental guard has pivoted at one end thereof at 8, a combined stripper and guard 9. This combined stripper and guard performs two functions. When 60 adjusted to the full line position, shown in Fig. 1, it coacts with the segmental guard and when adjusted to the dotted line position, shown in Fig. 1, it acts as a stripper for stripping the material cut by the cutting blade. This combined stripper and guard is substantially straight throughout the central portion and has laterally deflected end portions 9^a and 9^b, the end portion 9^a being pivoted, while the end portion 9^b is adapted 65 to be received on a notch or recess 10 formed in the other end of the segmental guard 7, so as to interlock with said end, as shown in Figs. 1 and 5. The portion 9^b also has a curved recess 9^c in its under side and the portion adjacent this recess is adapted to be received within a groove 11 formed in a washer or member 12, which is secured to the shaft 13 on which the cutting disk 2 is arranged. When the combined stripper and guard lies in this position, as illustrated 70 in dotted line Fig. 1, or in full line as in Fig. 6, it acts as a stripper for removing any material which is adhering to the blade 2.

75 The pivot 6 permits the segmental guard with the combined stripper and guard to be swung away from the cutting blade for the cleaning or the repair of the blade, and in order to sustain the segmental guard and combined stripper and guard in operative 80 relation to the cutting blade, a holding device is provided, preferably in the form of a double arm lever 18, pivoted at 19, to the frame 1 and having a laterally turned end 20 to engage said frame in order to limit the movement of the holding device in the other 85 direction. The other arm of the holding device cooperates with the pivot pin 8 of the segmental guard and holds the latter firmly against the side of the frame 1, thus preventing any movement in said segmental guard. 90 This point of engagement is particularly ad-

vantageous in that it reduces the vibration in the segmental guard and the combined stripper and guard to a minimum.

With the end in view of providing for collecting the cut material, a ledge or shelf 14 is provided, which has an upwardly extending flange 15 at its rear edge provided with a dove tail projection 16 adapted to be received within a dove tail notch 17, formed in 10 the segmental guard 7, adjacent the pivot 8. It is apparent that this connection permits the ready collection of the material cut by the cutting blade, while, at the same time, enables the collector to be removed and 15 cleaned.

From the foregoing it will be seen, that there has been provided an improved means for holding the segmental guard and combined stripper and guard in cooperative relation with the cutting blade. There is also provided a grooved member for engaging the free end of the combined stripper and guard, said member turning with the cutting blade and acting to hold the combined stripper and guard in cooperation with the cutting blade, while the latter turns. A collector for the sliced material is provided, which is effectively supported in a position where it will collect the material cut by the 30 cutting blade.

What I claim as my invention and desire to secure by Letters Patent is:

1. A slicing machine comprising a rotary cutter, a grooved member projected from one

side of the cutter in line with the axis of the cutter, a segmental guard for the cutter exposing a portion of the cutter, and a combined stripper and guard, pivotally connected to the segmental guard at one end of the latter, interlocking with the segmental guard 40 at the opposite end of the latter to act as a guard, and having a portion for engaging the grooved member to cause the stripper and guard to act as a stripper.

2. A slicing machine comprising a rotary cutter, a segmental guard for the cutter, pivotally mounted at one side of the cutter, a combined stripper and guard, pivotally connected to one side of the segmental guard and arranged to cover the exposed portion 50 of the cutter, and a device cooperating with the segmental guard adjacent the pivotal connection with the combined stripper and guard to hold the segmental guard in cooperative relation with the cutter.

3. A slicing machine comprising a rotary cutter, a segmental guard for the cutter, and a collector for the sliced material, supported from said segmental guard near one end of the latter.

4. A slicing machine comprising a rotary cutter, a segmental guard for the cutter, having near one end a dove tail notch, and a collector for the sliced material having a dove tail projection engaging in said dove tail 65 notch to support the collector from the segmental guard.

SOLOMON WILE.
